UNITED STATES PATENT OFFICE.

CHARLES A. CRUM, OF BRUNSWICK, GEORGIA.

PILE-SAWING MACHINE.

SPECIFICATION forming part of Letters Patent No. 763,161, dated June 21, 1904.

Application filed July 10, 1903. Serial No. 165,011. (No model.)

To all whom it may concern:

Be it known that I, CHARLES A. CRUM, a citizen of the United States, residing at Brunswick, in the county of Glynn and State of Georgia, have invented new and useful Improvements in Pile-Sawing Machines, of which the following is a specification.

My invention relates to improvements in pile-sawing machines, and pertains more particularly to that class carrying a pile-driver and in which the piles are cut off after they have been driven into the ground.

The object of my invention is to provide a machine of this character in which a circular horizontal saw is used and in which said saw is adapted to be moved in the arc of a circle and also adapted to be raised or lowered, and thus it will be readily seen that the saw is adapted to cut the piles at any desired height and also adapted to cut the piles in their different arrangement along the line of travel of the machine.

Another object of my invention is to provide a machine in which the saw is automatically fed forward as it works its way through the pile and in which the said saw is moved or caused to be moved at will in the arc of a circle by the main drive-shaft which drives the saw-operating mechanism.

A still further object of my invention is to provide a machine of this character in which the piles may be cut off in a horizontal plane or at an angle, as desired.

In the accompanying drawings, Figure 1 is a side elevation of my improved machine. Fig. 2 is a top plan of Fig. 1. Fig. 3 is an enlarged vertical sectional view of the saw-carrying carriage. Fig. 4 is an enlarged end view of the saw-carriage. Fig. 5 is a transverse sectional view. Fig. 6 is a longitudinal sectional view of the rear portion of my machine.

Referring now to the drawings, 1 represents a frame which in the form herewith shown is mounted upon wheels 2, but could be mounted upon a boat or any other desired device for which piles are adapted to be used. The said frame 1 is provided with standards 3, which form a frame thereabove, and the forward end 50 of the frame 1 is provided with a pile-driving

frame 4, which carries the usual weight 5, which is operated in the usual manner by an engine 6, which is mounted on the rear end of the frame, and through this mechanism the piles are first driven into the ground and afterward cut, as hereinafter more fully described. The frame 1 adjacent the forward end is provided with a segmental slot or opening 7, which has communicating therewith the radially-extending slots 8, which are shown 55 five in number; but any desired number may be used, as increasing the number of slots 8 only allows of a finer adjustment of the saws. In rear of said segmental slot 7 is a parallel segmental track 9, upon which is mounted the 60 saw-carriage 10. The said carriage 10 at its rear end is provided with grooved wheels or rollers 11, which are adapted to run on the base 1 just in rear of the segmental slot 7 and adapted to travel in a line parallel therewith. 70

The rear portion of the frame 1 is provided with the upwardly-extending oppositely-disposed elongated members 13 and 14, and extending transverse thereof and journaled therein is the main drive-shaft 15, which has 75 one end extending beyond the vertically-arranged member and has rigidly keyed thereon a disk-shaped member 16, which has its outer face provided with ratchet-shaped teeth 17, and loosely mounted on said shaft 15 beyond 80 the member 16 is the main drive-wheel 18, which is slidable thereon. The inner face of said wheel 18 is provided with ratchet-shaped teeth 19, and when the said wheel or gear is moved upon the shaft 15 the teeth 19 interlock with the teeth 17, carried by the member 16, and thus the drive-wheel 18 causes the shaft 15 to rotate. The said wheel 18 may be moved on the shaft 15 by a lever or any other well-known means, and the wheel 18 is driven 85 by an engine 20 in any well-known manner carried by the rear end of the frame 1. The shaft 15 intermediate the two upwardly-extending members 13 and 14 is provided with an enlarged beveled gear-wheel 21, which is 90 rigidly secured thereto. The said upwardly-extending members 13 and 14 intermediate their ends and in front of the shaft 15 are provided with a transverse bar 22, and below said bar 22 is a block 23, which is secured to the 95 100

base 1, but leaving a space between the upper end thereof and the said transverse bar 22. Pivotedly mounted between said transverse bar 22 and the block 23 is a journal 24, which is adapted to oscillate in a vertical plane. Said journal 24 is provided with a transverse opening 25, through which passes the main saw-driving shaft 26, which extends forward and is connected to the saw in a manner hereininafter more fully described. The rear end of said saw-driving shaft 26 is provided with a bevel-gear 27, which is adapted to mesh with the gear 21, carried by the shaft 15, and by means of which the shaft 26 is caused to revolve or rotate and by means of which the saw is revolved. The said block 23 is provided with a transverse opening 28 through which a rod 29 passes, and said rod is for moving the saw-carriage forward as the saw works its way through the pile. The said rod 29 extends rearwardly through the opening 28 in the block 23 and has its rear end journaled in a block 30, which extends transverse the frame 1, and said rod extends considerably beyond the block 30, so that the said rod is at all times journaled in said blocks 23 and 30 when the saw-carriage is pushed forward as far as possible. Intermediate the blocks 23 and 30 is a block 31, through which the rod 29 passes. Journaled between said blocks 31 and 30 are two worms 32 and 33, which have their rear journals extending through the block 30 and carry pinions 34 and 35, which are adapted to mesh with each other, and thus the driving of one worm causes the other worm to travel in the opposite direction. The worm 32 has its forward journal passing through the block 31 and mounted on said journal is a pulley-wheel 36. The main shaft 15 also carries a small pulley 37, and a belt 38 passes around the pulleys 37 and 36, and thus the two worms are driven in opposite directions. The rod 29 carries an upwardly-extending pin 39, which is normally held between the worms 32 and 33, but is adapted to be thrown in contact with either of said worms. The said rod 29 is provided with an arm 40, which is rigidly secured thereto. Connected to the upper end of said arm 40 is a link 41, which has its opposite end connected to a lever 42, which is pivoted at 43 to the transverse bar 22. Mounted on said transverse bar 22 is a U-shaped frame 44, which has journaled therein a shaft 45, which is parallel with the shaft 15, and mounted on said shaft 45 is a sleeve 45', which is keyed thereon against rotation, but adapted to slide thereon in either direction. Rigidly carried by sleeve 45' is a pulley 46. The shaft 15 is also provided with a pulley 47, which is rigidly mounted thereon, and passing around the pulleys 47 and 46 is a belt 48, by means of which the shaft 45 is driven. Loosely mounted on said shaft 45 on each side of the sleeve 45' is a drum 49 and 50, and passing around said drums 49 and 50 are the

cables 51 and 52, which extend forward and are secured to the saw-carriage 10, as will be hereinafter more fully described and pointed out. The sleeve 45' is provided on each side with projections 53, and the inner faces of the drums 49 and 50 are provided with projections 54. The sleeve 56 is provided with a groove 55, in which rests the lever 56, which has its lower end pivoted at 57 to the transverse bar 22, and thus it will be seen that the projections 53 are thrown in contact with the projections 54, carried by either of the drums, and thus it will also be seen that either of the drums are revolved, and the cables secured thereto are wound upon said drum, and the saw-carriage is moved upon the wheels or rollers in either direction.

The saw-carriage consists of an outer frame mounted upon the two pair of wheels 11 and 12, as heretofore described, which is adapted to be moved in an arc of a circle. Within this outer frame is saw-carrying member 58. The saw-carriage 10 in its lower face is provided with a groove 59, into which slides the bottom 60 of the saw-carrying member 58, and the upper edge of the carriage 10 is provided with grooves 60', which are adapted to receive the top 62 of the saw-carrying member 58. The member has journaled between the bottom 60 and the top 62 a vertical shaft 63, which carries a large pinion 64, which is rigidly secured to the shaft. Below said pinion and carried by the shaft 63 is a beveled gear-wheel 65, which is in mesh with a beveled gear-wheel 66, which is carried by the shaft 67, which is journaled in the rear wall 68 of the saw-carriage proper, 58. The said shaft 67 has an elongated square portion 68', which is adapted to fit in an elongated square recess 69 in the end of the shaft 26, and thus it will be seen that as the saw-carrying member 58 is moved outwardly the shaft 67 slides within the shaft 26; but both are caused to rotate. The shaft 26 having its inner end journaled in the pivoted bearing 24 is thus allowed to swing in the arc of a circle, the same as the saw-carriage travels in the same line. The frame 1 is provided with a raised track 70, which is also arranged in an arc of a circle, and the shaft 26 carries a member 71, in which the shaft 26 is adapted to rotate, and the outer end of said member carries the grooved pulleys 72 and 73, which are adapted to travel on the track 70, and thus the shaft 26 is supported in a horizontal line, preventing friction or binding between the shaft in the coupling. The lower face of the saw-carrying member at its forward end is provided with an opening 74, in which rests a block 75, which is adapted to oscillate in said opening, and said block having an opening 76, through which a vertically-arranged saw-shaft 77 is adapted to pass, and the upper end of said shaft 77 passing through an elongated transverse opening 78 in the upper portion of the saw-carriage.

Secured or swiveled to the upper end of said shaft 77 is a block 79, by means of which the said shaft and saw is supported, and secured to the upper end of said block is a supporting-cable 80, which passes up over the frame 3, and thus it will be seen that the saw-shaft is either raised or lowered, yet it is supported in such a manner that it readily rotates. Mounted on said shaft 77 below the upper portion of the saw-carriage is a pinion 81, which is held against rotation thereon, but yet is adapted to slide on the shaft, thus allowing of the raising and lowering of the said shaft. The under side of the upper portion of the saw-carriage carries a support 82, which is adapted to support the gear-wheel 81 at its proper height in order that it will at all times mesh with the pinion 64, carried by the vertical shaft 63. The said support 82 has a central supporting portion 83 and the two outer oblique supporting-walls 84 and 85, which are adapted to support the said pinion 81 in an oblique line when the saw-shaft 77 is moved at an angle to saw the piles at an angle.

25 The elongated transverse opening 78 in the upper portion of the saw-carriage is provided with a recess 86 surrounding the same, and said recess being segmental in cross-section, or, in other words, having its outer ends 87 and 88 gradually curved deeper. The saw-shaft 77 above the saw-carriage has surrounding the same a sleeve 89, which is provided with the downwardly-extending portion 90, which is adapted to travel in the segmental opening 78. The said sleeve is provided with an outwardly-extending arm 91, which is pivotally connected to a lever 92, which is pivoted at 93 to the top of the saw-carriage, and thus it will be seen that by moving said lever 40 in either direction the saw-shaft is thrown and held at an angle. The lower end of said shaft 77 is provided with the usual circular saw 94, which is rigidly secured thereto and adapted to rotate therewith.

45 The outer end of the rod 29 is provided with a ball 95, which is adapted to fit in a socket 96, carried by the inner end of the rod 97, and the outer end of said shaft is rigidly secured to the movable saw-carriage, and thus it will 50 be seen that the outward movement of the shaft 29 will force the saw-carriage outward and also allow of the carriage moving in the arc of a circle, as heretofore described.

The frame 1 has secured adjacent its outer edge in front of the track 70 pulleys 98 and 99, and passing through or over said pulleys are cables 51 and 52, which have their outer ends 102 and 103 secured to the sides of the saw-carriage and their inner ends passing under the raised track 70 and are secured to the drums 49 and 50.

The lower face of the outer saw-carriage is provided with a slot 104, which allows the saw-shaft to move outwardly when the inner saw-carriage is forced outwardly.

The operation of my machine is as follows: The engine 20 is first started, which is adapted to drive the wheel 18, and by means of the clutch member 16 the said wheel is coupled to the shaft 5, and through the medium of the 70 beveled gears 21 and 27, the shaft 26, and the gears 66, 65, 64, and 81 the saw-shaft is driven. The saw-shaft, as before described, is raised and lowered by the cable 80, which is secured to the upper end thereof, and thus 75 the saw is raised and lowered, and the piles may be cut at any desired height. Through the medium of a belt 38 and pulleys 36 and 37 and the intermeshing gears 34 and 35 the two worm-gears 32 and 33 are driven in opposite directions, and thus when the pin carried by the shaft 29 is thrown in engagement with one of said worm-gears the saw-carriage is pushed forward and when thrown in engagement with the other worm-gear the saw-carriage is drawn backward, and thus the saw is fed as it cuts its way through the pile. When it is desired to move the saw-carriage in an arc of a circle to adjust the saw to the different piles, the lever 56 is drawn over, so 80 that the member 53 engages either the drum 49 or 50, and thus the cable is wound thereon and the saw-carriage drawn over toward that side of the frame, while the cable on the opposite drum is free to unwind. The lever 95 92 is adapted to throw the saw-shaft at the desired angle for cutting the piles at any desired angle.

Having thus described my invention, what I claim as new, and desire to secure by Letters 100 Patent, is—

1. A sawing-machine, comprising a frame, a laterally and longitudinally adjustable saw-carriage mounted thereon, a driving mechanism mounted on the opposite end of the frame, 105 and a telescoping shaft connecting the saw within the carriage and the driving mechanism.

2. A sawing-machine comprising a frame, a laterally and longitudinally adjustable saw-carriage mounted thereon, a driving mechanism mounted on the opposite end of said frame, a telescoping shaft connecting the saw within the carriage and the driving mechanism, and a longitudinally-slidable shaft adapted to move 110 said saw-carriage.

3. A sawing-machine comprising a frame, a laterally and longitudinally adjustable saw-carriage mounted thereon, a driving mechanism mounted on the opposite end of the frame, a telescoping shaft connecting the saw-carriage with the driving mechanism, a longitudinally-slidable shaft adapted to move said saw-carriage longitudinally, and a mechanism operated by the driving mechanism for moving the saw-carriage laterally.

4. A sawing-machine comprising a frame, a laterally and longitudinally adjustable saw-carriage mounted thereon, a driving mechanism on the opposite end of said frame, means carried by said driving mechanism for driv- 125 130

ing the saw, and means carried by said driving mechanism for moving the saw-carriage laterally or longitudinally.

5. A sawing-machine, comprising a frame, 5 a saw-carriage laterally adjustable thereon, a saw-carrying member longitudinally adjustable within said saw-carriage, a rotary saw carried by said saw-carrying member, a driving mechanism carried by the opposite end of 10 said frame, an operative connection between said driving mechanism and said saw, means operated by said driving mechanism for moving said saw-carriage laterally and said saw-carrying member longitudinally.

15 6. A sawing-machine comprising a frame, a saw-carriage laterally adjustable thereon, a saw-carrying member longitudinally adjustable within said saw-carriage, a saw-driving mechanism operatively connected to the saw, 20 and operative connections between said saw-carriage and saw-carrying member, and the driving mechanism, whereby they are adjusted independent of each other.

7. A sawing-machine comprising a frame, 25 a saw-carriage laterally adjustable thereon, a saw-carrying member longitudinally adjustable with said saw-carriage, a driving mechanism carried by the opposite end of said frame, a telescoping shaft connecting said saw and said driving mechanism, a longitudinally-slidable shaft connected to said saw-carrying member and said driving mechanism, and means operated by the driving mechanism for moving the saw-carriage laterally.

30 8. A sawing-machine, comprising a frame, and a laterally and longitudinally adjustable saw-carriage, a saw carried thereby and means carried by said frame for driving said saw, and means operated by said driving mechanism for moving the saw-carriage longitudinally and laterally.

9. A sawing-machine comprising a frame, a laterally and longitudinally adjustable saw-carriage carried thereby, a vertically-adjustable saw carried by said carriage, means carried by said frame for driving said saw, and means operated by said driving mechanism for moving the saw-carriage longitudinally and laterally.

45 50 10. A sawing-machine comprising a frame, a laterally and longitudinally adjustable saw-carriage carried thereby, a vertically-adjustable saw carried by said carriage, a driving mechanism carried by the opposite end of said frame, a telescoping shaft having its forward end operatively connected to said saw, a pivoted journal through which the rear end of said shaft is adapted to pass, means carried by the driving mechanism for driving said shaft, 55 a longitudinally-adjustable shaft having a ball-and-socket joint intermediate its ends and having its forward end secured to the saw-carriage and its rear end in operative connection with said driving mechanism, and means oper-

ated by said driving mechanism for moving 65 the saw-carriage laterally on said frame.

11. A sawing-machine comprising a frame, a longitudinally-adjustable saw-carriage, a saw carried thereby, a saw-driving mechanism, parallel worms driven by said driving mechanism, a longitudinally-slidable shaft below said worms and having its forward end connected to the saw-carriage, and a pin carried by said shaft and adapted to be thrown into engagement with either of said worms. 75

12. A sawing-machine comprising a frame, a longitudinally-adjustable saw-carriage, a saw carried thereby, a saw-driving mechanism carried by the frame, parallel worms driven by said driving mechanism in opposite directions, 80 a longitudinally-slidable shaft below said worms, and having its forward end connected to the saw-carriage, a pin carried by said shaft between said worms and means for oscillating said shaft, whereby the said pin is thrown into 85 engagement with either of said worms.

13. A sawing-machine comprising a frame, a longitudinally and transversely adjustable saw-carriage, a longitudinally-extending shaft, a ball-and-socket joint between said shaft and saw-carriage, and means for moving said shaft endwise in either direction. 90

14. A sawing-machine, comprising a frame, a longitudinally and laterally adjustable saw-carriage, means for adjusting said carriage laterally, an endwise-movable shaft formed of two sections and having a swivel connection, the forward end of said shaft connected to the saw-carriage, and means for adjusting said shaft endwise adjacent the opposite end. 95

15. A sawing-machine comprising a table having an arc-shaped slot therein and radially-extending slots communicating therewith, a saw-carriage above said slots, a saw-carrying member within said carriage, a vertically-arranged saw-shaft mounted in said saw-carrying member, means for moving said saw-carriage laterally on the table, and means for moving said saw-carrying member longitudinally within said saw-carriage. 100

16. A sawing-machine comprising a table having an arc-shaped slot therein and radially-extending slots communicating therewith, a saw-carriage having a lateral movement on said frame, a saw-carrying member having a longitudinal movement with said saw-carriage, and a vertically-arranged saw-shaft mounted in said saw-carrying member and adapted to travel within said arc-shaped and radial slots. 105

17. A sawing-machine, comprising a saw-carriage having a longitudinally-pivoted journal in its lower face, a vertical saw-shaft journaled therein and vertically adjustable, the upper end of said shaft passing through an elongated transverse opening in the upper end of the saw-carriage, means for holding the said shaft in its adjusted position in the horizontal 110

slot, and a member swiveled to the upper end of the said shaft and adapted to support the same.

18. A sawing-machine, comprising a saw-carriage having a horizontally-pivoted journal in its lower face, a vertical saw-shaft journaled therein and vertically adjustable, the upper end of said shaft passing through an elongated transverse opening in the upper end of the saw-carriage, means for holding the said shaft in its adjusted position in the horizontal slot, a member swiveled to the upper end of said saw-shaft, and a cable secured to said member, whereby the shaft is vertically adjustable and supported, yet adapted to freely rotate.

19. A sawing-machine comprising a saw-carriage, a horizontally-pivoted journal in its lower face, a vertical saw-shaft journaled therein and vertically adjustable, the upper end of said shaft passing through an elongated transverse opening in the upper end of the saw-carriage, means for holding the said shaft in its adjusted position, a gear-wheel loosely mounted on said saw-shaft, yet held against rotation, and means carried by the carriage for supporting the gear-wheel in its proper position, and means carried by the carriage for driving said gear whereby the shaft is driven.

20. A sawing-machine comprising a saw-carriage, a horizontally-pivoted journal in its lower face, a vertical saw-shaft passing through said pivoted journal and vertically adjustable, the upper end of said shaft passing through an elongated transverse opening in the carriage, means for holding the said shaft in its oblique adjusted position, a gear-wheel loosely mounted on said saw-shaft, but held against rotation, and a support carried by the carriage adapted to support the said gear-wheel in a horizontal or an oblique position, and means carried by the carriage for driving the said gear, whereby said saw-shaft is driven.

21. A sawing-machine comprising a saw-carriage, a saw-shaft vertically and obliquely adjustable therein, a gear-wheel carried by said shaft within the carriage and means carried by the carriage for supporting the gear-wheel in a horizontal or vertical position.

22. A sawing-machine comprising a saw-carriage, a saw-shaft vertically and obliquely adjustable therein, a gear-wheel carried by said shaft within the carriage, and a support carried by said carriage and having a horizontal central supporting-face and an oblique supporting-face on each side and adapted to support the said gear-wheel.

23. A sawing-machine comprising a saw-carriage, a saw-shaft vertically and obliquely adjustable therein, a gear-wheel loosely carried by the shaft within the carriage, a support carried by said carriage and having a horizontal central supporting-face, and an oblique supporting-face on each side and adapted to support the said gear-wheel, a gear-wheel carried by said carriage and in mesh with said first

gear-wheel and means for driving said second gear-wheel.

24. A sawing-machine comprising a saw-carriage having a horizontally-pivoted journal in its lower wall, a vertically-adjustable saw-shaft passing through said pivoted journal and vertically adjustable, the upper end of said shaft passing through an elongated transverse opening in the top of the carriage, means for holding said shaft in its adjusted position in said slot, a gear-wheel loosely mounted on said saw-shaft but held against rotation, a support carried by the carriage having a central horizontal supporting-face and an oblique supporting-face on each side thereof for supporting the gear-wheel, a vertical shaft mounted in said carriage, a gear carried thereby and meshing with the gear-wheel carried by the saw-shaft, a beveled gear-wheel carried by said second shaft, a horizontal shaft carried by said carriage and having a beveled gear carried by its inner end and meshing with the first beveled gear, and means for driving said shaft.

25. A sawing-machine comprising a frame, a horizontal and laterally movable saw-carriage mounted on said frame, a vertically and obliquely movable saw-shaft carried by said carriage, a driving mechanism on the rear end of said frame, a telescoping shaft connecting said carriage and driving mechanism and adapted to drive said saw-shaft, a longitudinally-movable shaft rigidly secured to said carriage and movable by said driving mechanism, a drum-carrying shaft operated by said driving mechanism, and a cable wound upon said drums and adapted to move the saw-carriage laterally on the frame.

26. A sawing-machine comprising a horizontally and laterally movable saw-carriage mounted on said frame, a vertically-arranged saw-shaft carried by said carriage, a horizontally-arranged shaft carried by said carriage and adapted to drive the saw-shaft, a second shaft adapted to receive the end of the first shaft, a wheeled support through which said second shaft is adapted to loosely pass, and a track upon which said wheel-support is adapted to travel when the carriage is moved.

27. A sawing-machine comprising a frame having a slot extending across the front end of the same, and having radially-extending slots communicating therewith, a saw-carriage mounted on wheels and adapted to travel on a track carried by said frame in rear of said slot, a saw-carrying frame within the carriage and having a vertically-arranged downwardly-extending saw-shaft adapted to travel in said transverse slot and radial slots.

28. A sawing-machine comprising a frame having an arc-shaped slot extending across the front end of the same, radially-arranged outwardly-extending slots communicating with the outer edge of said arc-shaped slot, a saw-carriage having wheels on its lower face and

- adapted to travel on a track carried by the frame in rear of said slot, a saw-carrying frame within the carriage and outwardly movable therein and a vertically - arranged saw-shaft carried by said saw-carriage member and adapted to travel in either the arc-shaped slot or the radially-extending slots.
29. A sawing-machine comprising a frame having a laterally and longitudinally movable saw-carriage, a driving mechanism in rear of said carriage, means operated by the driving mechanism for moving the carriage longitudinally, a shaft adjacent said driving mechanism, a pulley loosely mounted on said shaft and rotated by said driving mechanism, a drum for said shaft on each side of said pulley, cables passing around said drums, and secured to the said saw-carriage, and means for connecting said pulley to either of the drums.
30. A sawing-machine comprising a frame having a laterally and longitudinally movable saw-carriage, a saw carried thereby, a driving mechanism carried by the opposite end of the frame, a connection between said driving mechanism and said carriage, two worms carried by said frame and driven in opposite directions, a longitudinal endwise-movable shaft having a ball-and-socket joint intermediate its ends, a pin carried by said shaft and extending between said worms, an arm carried by said inner portion of the shaft, a link secured to said arm and an intermediately-pivoted lever secured to said link, whereby the pin is adapted to be thrown into engagement with either of said worms, and thus the shaft is adapted to be moved in and out.
31. A sawing-machine comprising a table having an arc-shaped slot therein, and radially-extending slots communicating therewith, a saw-carriage mounted upon said frame and having a lateral movement, a saw - carrying member within said saw-carriage and having a longitudinal movement therein, a saw-shaft

vertically adjustable within said saw-carriage and having an oblique movement therein, and 45 said shaft adapted to travel within said arc and radial slots.

32: A sawing-machine comprising a frame, a laterally - adjustable saw - carriage carried thereby, means for adjusting the same, a longitudinal adjustable saw - carrying member within said saw-carriage, a vertically and obliquely adjustable saw carried by said saw-carrying member, means for rotating said saw, oppositely-rotating worms driven by said saw-driving mechanism, a rod connected to said saw-carrying member, an upwardly-extending member carried by said rod, and means for causing said member to engage either of said worms, whereby the saw-carrying member is drawn in or out.

33. A sawing-machine comprising a frame, a laterally - adjustable saw - carriage carried thereby, a longitudinally-adjustable saw-carrying member within said saw-carriage, a vertically and obliquely adjustable saw-carrying shaft carried by said saw-carrying member, means for rotating said saw-shaft, a transverse shaft carried by the frame, means driven by said shaft for moving the saw-carriage transversely the frame, two parallel worms oppositely driven by said transverse shaft, a rod connected to said saw-carrying member, an upwardly-extending member carried by the rod between the worms, and means for causing 75 said member to engage either of said worms, whereby the saw-carrying member is moved in or out.

In testimony whereof I have hereunto set my hand in the presence of two subscribing 80 witnesses.

CHARLES A. CRUM.
